PUMP

Bernard Beaman, Julius Hulman, and Robert A. Stein, Dayton, Ohio; said Beaman and said Stein assignors to said Hulman

Original application June 8, 1945, Serial No. 598,356. Divided and this application October 21, 1948, Serial No. 55,742

2 Claims. (Cl. 103—162)

(Granted under the act of March 3, 1883, as amended April 30, 1928; 370 O. G. 757)

1

The invention described herein may be manufactured and used by or for the Government for governmental purposes without the payment to us of any royalty thereon.

Our present invention relates in general to a hydraulic pressure pump of two-stage character such as disclosed in our copending application, Serial No. 598,356, filed June 8, 1945, which matured into Patent No. 2,495,685, on January 31, 1950, from which this application is a division. The pump there shown is designed for efficient operation at extremely high pressures in the second stage.

One object of the present invention is to provide a pump structure of the type having a rotating barrel provided with cylinder bores in which pistons are slideable by engagement with a cam, wherein an increased pressure thrust of the cylinder barrel against a valve plate is secured by reducing the unseating pressure force on the area between the barrel cylinder openings and the barrel land area, such construction involving a valve port diameter less than the cylinder circle diameter and permitting of multiple drilled passageways from the ends of the cylinders to the valve ports so that the flow area can be made the desired value, and the drilled passageways being at an angle produce an elliptical intersection between the drilled passageways and the valve ports in a plane face at the end of the cylinder barrel.

With this main object in view, as well as other minor objects that will be developed as the description of our invention proceeds, the construction, arrangement and combination of the various parts of our pump structure will hereinafter be more fully set forth, pointed out in our claims and illustrated in the accompanying drawings, wherein:

Figure 1 is a vertical sectional view through a pump structure embodying our present invention and corresponds in general to Figure 4 of our copending application with the porting arrangement of Figures 15 and 16 thereof applied to Figure 4.

Figure 2 is a sectional view on the line 2—2 of Figure 1 taken at the parting face between the housing and the end plate of the pump and thereby showing the housing in end elevation, Figure 1 being taken on the section line 1—1 thereof, and

Figure 3 is a sectional view on the line 3—3 of Figure 1 to show particularly the cam for actuating the pistons of the pump.

On the accompanying drawing, we have used

the reference numeral 10 to indicate a cylindrical housing. The housing has a flange 12 at one of its ends for mounting the pump on an air craft engine or the like. For this purpose bolts or screws may extend through suitable perforations of the flange 12 and thread into the engine or any suitable support in the usual manner.

The housing 10 has a flange 16 at its other end to which an end plate 18 is secured as by cap screws 20 with a suitable gasket or sealing compound between the flange 16 and the end plate.

The housing 10 has an internal partition 22 against which a back plate 23 is positioned and secured in such position. A cam 24 is affixed to the back plate 23 so as to be stationary in relation thereto. The cam fits the interior of the housing 10 and is retained against rotation by a pair of dowels 19 and 21. The cam 24 has a cam face 28 which is in the form of a truncated cylinder end, and a hardened creep plate 30 of washer-like character for engaging against this face.

Rotatable in a bearing sleeve 32 of the end plate 18 and in a bearing surface 34 of the cam 24 is a barrel drive shaft 36. Loosely splined at 42 on the barrel drive shaft 36 is a barrel 44 having an annular shoulder 46 engaging the shaft 36 for guide purposes. The barrel 44 has a pair of annular lands 50 and 51 to contact with a flat sealing face 52 of the end plate 18. The loose splining of the barrel 44 to the shaft 36 permits ready conformity of the lands 50 and 51 to the face 52.

Circumferentially spaced cylinder bores 54 are provided in the barrel 44 and in each a plunger-like piston 56 is reciprocable. The cylinders 54 and the pistons 56 constitute a high pressure pump. Each cylinder has a pair of cylinder ports 58 which are of somewhat less cross sectional area than the area of the cylinder bore in order to provide the necessary thrust force between the barrel 44 and the end plate 18 by internal pressure acting on the cylinder bore ends surrounding the ports 58.

The barrel 44 is adapted to be seated against the end plate 18 by hydraulic pressure within the pump housing 10 as will hereinafter appear. During starting of the pump, when pressure has not yet built up, it is desirable to make sure that the faces 50 and 51 are in contact with the face 52 and this may be accomplished by a light spring 59.

A low pressure pump is provided in the form of a rotor 38 having slots in which vanes 48 are

slidably mounted, the rotor being within a stator bore 60 of the cam 24 which stator bore is eccentric with relation to the rotor to thereby effect inward and outward movement of the vanes 48 in a well-known manner and as disclosed in our parent application.

A low pressure inlet boss 62 is provided on the end plate 18 and communicates with a passageway 64 in the end plate which in turn communicates with an intake passageway 66 in the housing 10. The passageway 66 communicates with the interior of the dowel 21 through openings 68 therein and the interior of the dowel communicates with an intake port 70 formed in the back plate 23. This port feeds liquid into the intake side of the low pressure pump (lower side in Figure 1).

An outlet port 72 is provided on the high pressure side of the lower pressure pump and this outlet communicates through openings 74 in the dowel 18 with an outlet passageway 76 which extends to the inner face 52 of the end plate 18 and communicates with a C-shaped passageway 78 formed at the end of the housing 10 adjacent the plate 18. The passageway 78 communicates with an arcuate intake port 82 of the end plate 18 as shown by dot and dash lines in Figure 2 and in greater detail in our parent application so that oil can be drawn into the cylinder bores 54 through the ports 58 when they register with the port 82, the intake port 82 of course being for the high pressure pump.

The ports 58 successively register with an outlet port 84 (also shown by dot and dash lines in Figure 2) which is also arcuate in shape and communicates directly with an outlet or high pressure boss 86 on the end plate 18. The boss 86 is the outlet and the boss 62 is the inlet and accordingly there is low pressure in the boss 62 and high pressure in the boss 86 as indicated by the legends "HI" and "LO" adjacent the arrows in the bosses 86 and 62, respectively in Figure 1.

The dowel 19 is threaded in position and can accordingly be removed. The dowel 21 is also removable so that the pump action may be reversed by reversing the plate 23 in the housing 10 as fully explained in our parent application.

The rotor 38 is formed on a shaft 104 which rotates in a bearing surface 106 of the back plate 23 and is connected to the barrel drive shaft 36 by a loosely splined connection 108 and with a drive shaft 110 by means of a loosely splined connection 112. The drive shaft 110 has a splined end 114 for connection to a power take-off shaft of an aircraft engine or any other suitable means to drive the pump. Such means would align the outer end of the drive shaft 110 for proper operation without binding.

The drive shaft 110 has a flange 116 surrounding it with which a seal plate 118 in the form of a ring is engageable. A spring 120 effects such engagement initially, whereas fluid pressure within the housing effects the engagement after the pump is in operation. The spring 120 is seated against a second end plate 122 secured to the partition 22 by suitable means such as screws 124.

The seal plate 118 is sealed relative to the housing 10 by means of a diaphragm 126 having its inner end clamped to the seal plate by a spanner nut 128 and its outer edge clamped between a washer 130 and the end plate 122 by the screws 124. This provides a pressure chamber indicated at 132 inside of the flange 116.

The inner end of the drive shaft 110 is seated

against a shoulder 134 of the rotor shaft 104 which serves merely as a thrust connection but normally when the pump is operated the two are spaced from each other. A passageway 136 is provided through the center of the rotor shaft and communicates with a passageway 138 through the center of the barrel shaft 36 through which liquid is adapted to flow after passing through the splined connections 112 and 108. A relief groove 140 is provided for such flow in the event that the inner end of the drive shaft 110 is seated against the shoulder 134.

The passageway 138 communicates with a pressure relief valve in the form of a valve plug 142 seated against a ring 144 by a spring 146. The valve plugs act as a piston in a sleeve 148 which serves to guide its sliding movement. The sleeve 148 has a head 150 for screwing the sleeve into the end plate 18 at a screw threaded connection 152. The sleeve 148 has ports 154 communicating with an annular groove 156 which in turn communicates by means of a passageway 158 with the low pressure boss 62.

The low pressure pump comprising the rotor 38 and the vanes 48 is higher capacity than the high pressure pump comprising the cylinders 54 and the pistons 56. This is for the purpose of assuring full charge of the high pressure cylinders for reducing voids in the liquid and for keeping the pistons in contact with the creep plate 30. To avoid excessive build-up of pressure and to keep a substantially even charging pressure from the low pressure pump to the high pressure pump, a relief valve from the outlet of the low pressure pump to its inlet may be provided as disclosed in our parent application.

The porting arrangement 58 is the main feature of our present invention, the other features thereof being claimed in our parent application. These ports, it will be noted, are drilled at an angle instead of extending axially into the ends of the bores 54. This results in their outer ends terminating in elliptical port openings as shown in Figure 2 which are closer to the center of rotation than the axes of the cylinders 54. This provides increased pressure thrust of the barrel 44 against the valve plate 18 as it reduces the unseating pressure force on the area between the barrel cylinder openings and the barrel land area. This is basically produced by reducing the radii of the ports 82 and 84 in the end or valve plate 18 so that their diameter is less than the cylinder circle diameter.

Any number of the ports 58 may be used (two are shown by way of illustration) per cylinder as required to provide the desired flow passage. The barrel is preferably provided with a pair of circular lands instead of having a plane face, these being the lands indicated at 59 and 51. The land 59 is in alignment with the cylinder circle diameter and thus acts as a stabilizing land. The land 51 for the ports 58, 82 and 84, it will be noted, is brought inside the cylinder circle diameter.

Practical operation

The shaft 110 is driven by any suitable power means to thereby drive the rotor shaft 104 and the barrel shaft 36. The rotor 38 and the barrel 44 are thereby driven and rotation of the rotor causes liquid to be drawn in from the intake boss 62 through the passageways 64, 66, 68 and 70 to the low pressure pump. The liquid therein is pumped out through the passageways 72, 74, 76, 78, 80 and 82 to the pistons 56 on their inward

strokes while their cylinder ports 58 communicate with the intake port 82.

Rotation around the other half of the circle causes the pistons to be forced outwardly in the cylinders 54 (see upper piston in Figure 3) for forcing the oil into the high pressure outlet passageway 84 and the outlet boss 86. The liquid is thus pumped at low pressure by the vane pump and at high pressure by the piston pump which is charged by the lower pressure vane pump, and the pressure in the outlet 86 may be relatively high such as 3,000 pounds per square inch in the particular design of pump illustrated.

During operation the spring 59 keeps the barrel 44 in engagement with the end plate 18 and the spring 120 keeps the seal plate 118 in engagement with the flange 116 so that there is a sealed chamber within the housing 10 extending from the end plate 18 to the diaphragm 126. These springs, particularly the spring 59, maintain the seal necessary for priming the pump. There is some leakage of liquid past the faces 50, 51 and 52, especially before pressure is built up in the housing 10 and this liquid together with the small amount which creeps past the pistons 56 and any which may leak from the low pressure pump will charge the interior of the housing 10 for lubricating the bearing surfaces 32, 34 and 106 and produce a pressure within the housing.

The barrel 44 will be seated against the end plate 18 under the action of the charging pressure for the housing plus the internal pressure of the cylinder bores acting on the partially closed cylinder ends. The pressure also acts on the flange 80 to compress the spring 120 somewhat and thereafter maintain the flange 116 against the sealing face of the seal plate 118 under such pressure. The pressure is limited however by the relief valve 142 beyond the strength of the spring 146. The liquid pressure will move the relief valve to a relief position permitting the excess liquid to flow through the ports 154, 156 and 158 back to the lower pressure boss 62. A selected spring 146 may be used as required to keep a desired pressure within the housing. The valve 142 therefore acts as a pressure regulating valve.

Our two-stage pump can be readily adjusted for a reversal in the direction of rotation by removing the dowels 19 and 21, rotating the back plate 23 a half turn and re-inserting the dowels in the manner described in our parent application.

From the foregoing specification we believe it will be obvious that we have provided a structure which compactly includes both a low pressure pump and a high pressure pump whereby a complete hydraulic pump suitable for high pressure operation is had. Increased pressure thrust of the barrel 44 against the end plate 18 is had by reducing the unseating pressure forces at the parting line between these two elements. This is accomplished by reducing the circle diameter of the ports 58 to less than that of the cylinder bores in the novel manner disclosed. This also has the added advantage of reducing the circle diameter of the ports 82 and 84 and permitting the use of multiple passages 58 which are slightly increased in area at the ends thereof where they match the ports 82 and 84 by being

drilled at a slant so as to be elliptical rather than truly round in cross section at their terminal ends at the land 51.

Some changes may be made in the construction and arrangement of the parts of our pump without departing from the real spirit and purpose of our invention, and it is our intention to cover by our claims any modified forms of structure or use of mechanical equivalents which may be reasonably included within their scope.

We claim as our invention:

1. In a hydraulic pressure pump of the character disclosed, a housing, a barrel driving shaft journaled therein, a barrel loosely mounted on said shaft for rotation therewith and being provided with cylinder bores, an end plate for said housing, said barrel being engaged therewith under fluid pressure against partially closed ends of said cylinder bores, pistons in said cylinder bores, a cam for reciprocating said pistons, said end plate having ports and said barrel having inwardly slanting openings for providing fluid communication between said cylinder bores and said ports in said end plate terminating at the end of said barrel in alignment with said ports, said barrel having a continuous uninterrupted circular land at the cylinder circle diameter and a second circular land of smaller diameter at the terminals of said slanting openings.

2. In a hydraulic pressure pump of the character described, a housing, a barrel driving shaft journaled therein, a barrel on said shaft, an end plate having a flat surface against one end of said housing, said barrel being engaged with said flat surface and having a plurality of cylinder bores, pistons therein, a cam for reciprocating said pistons, said end plate having C-shaped inlet and outlet ports for said cylinder bores arranged on a circle smaller than the cylinder bore circle diameter, said barrel having connecting slanting passages extending in straight direct lines from said bores to the end of said barrel where they register with said ports and a pair of circular lands, one coincident with said smaller circle and the other coincident with said cylinder bore circle diameter.
